BY *Thomas J. Hughes*

ATTORNEY

any accumulation of sewage thereon. It will be apparent that the several parts comprising my device, when disassembled can be compactly carried in a relatively small closure. Furthermore, as the inside diameters of drain passages and pipes leading thereto are of standard but varying sizes, a number of assembled sleeve and disk units may be carried so as to provide a disk structure adaptable for working fit in any size drain passage or pipe.

The assembly and operation of my device is as follows:

The upper rod portion 10 is threadedly secured in the bore 17 of the head 13 carried by the lower rod portion 12, so as to form therewith a unitary rod structure. The piston member, generally indicated (Fig. 4) by the numeral 26 (but consisting of sleeve 19, metal disks 20-20', flexible disk 22, and nuts 24 and 25) having previously been assembled as a unit, is slid onto the rod 12, with which sleeve 19 has a sliding fit. Finally nut 14 is threadedly secured to the lower end of rod 12. Thus piston 26, disposed about rod 12, is limited in use to a reciprocating movement defined by the stops 15 and 16.

In operation, when the plunger is inserted in a drain or waste pipe, as shown in Figs. 1 and 4, the lip of flexible strip 22, extending beyond the outer circular limits of metal disks 20-20', provides a substantially air-tight contact with the interior wall of said pipe. Upon reciprocation of the rod 10-12 the slidable mounting of the disk-piston 26 thereon permits easy ingress and egress and operation of the piston in the pipe. This because the end stops 15 and 16, upon reciprocation of the aforesaid rod, provide means whereby the piston can be given additional blows to move it in the desired up and down direction, and particularly, to urge the piston to greater depths within the pipe so as to exert a maximum amount of pressure against a clogging obstruction.

It is now obvious that I have produced a suction-pressure plunger which is simple in construction and highly efficient in operation and which may be readily assembled or disassembled, and also may be easily and quickly maintained in a clean condition. Although I have shown and particularly described the preferred embodiment of this invention, I do not wish to be limited to the exact construction shown, as various changes in the form and relation of the parts thereof may be made without departing from the spirit of this invention, as set forth in the appended claims.

I claim:

1. A portable pressure suction plunger for removing obstructions from drain pipes, comprising a rod having a bore, a head secured to one end of said rod, a sleeve slidably mounted on said rod between the head and the other end of said rod, a flat flexible pressure and suction disk mounted on said sleeve of a diameter slightly greater than the drain pipe, a pair of metal disks on said sleeve arranged one on each side of said flexible disk having a diameter slightly smaller than the diameter of said flexible disk, and retaining nuts threaded on the opposite ends of said sleeve for clamping engaging said metal disks and urging them into contactual engagement with the flexible disk.

moving and dislodging obstructions in drain pipes, comprising a rod, a handle on one end of said rod, a pair of abutment stops on the other end of said rod arranged in spaced apart relation, a sleeve slidably mounted on said rod between said stops and of a length less than the spacing between said stops, a flat flexible pressure and suction disk mounted on said sleeve of a diameter slightly greater than the drain pipe, a pair of metal disks on said sleeve arranged one on each side of said flexible disk having a diameter slightly smaller than the diameter of said flexible disk, and retaining nuts threaded on the opposite ends of said sleeve for clamping engaging said metal disks and urging them into contactual engagement with the flexible disk.

2. A portable pressure suction plunger for removing and dislodging obstructions in drain pipes by impact pressure forces, comprising a rod, a handle on one end of said rod, a pair of spaced apart abutment stops on the other end of said rod, an impact plunger movably mounted between said abutment stops comprising an externally threaded sleeve having a central bore of sufficient size to permit the same to slide freely on said rod in longitudinal to and fro directions between said abutment stops, said sleeve being of a length smaller than the spacing distance between said stops, a flat flexible plunger disk mounted on said sleeve having a diameter slightly greater than the internal diameter of the drain pipe, a pair of metal disks smaller in diameter than the flexible disk mounted on said sleeve and arranged one on each side of said flexible disk, and a pair of clamping nuts mounted on the opposite ends of said sleeve for locking said disks thereon, whereby reciprocating movement of said handle will cause said stops to alternately engage said sleeve and exert impact forces on the plunger which are transmitted to the obstruction in the pipe through the column of fluid therein.
